UNITED STATES PATENT OFFICE.

NAZZARENO SCARPONI, OF DOVER, NEW HAMPSHIRE.

SOFTENING DEVICE FOR SHOES.

1,209,889.

Specification of Letters Patent. Patented Dec. 26, 1916.

Application filed August 14, 1916. Serial No. 114,742.

To all whom it may concern:

Be it known that I, NAZZARENO SCARPONI, of Dover, in the county of Strafford and State of New Hampshire, a citizen of the United States, have invented a new and useful Improvement in Softening Devices for Shoes, of which the following is a full, clear, and exact description, reference being had to the accompanying drawings, forming a part of this specification in explaining its nature.

The present invention relates to a softening device for treating shoes during the process of their manufacture and more especially to a device for moistening and thereby softening the toe portion of the upper preparatory to the lasting of the shoe. The moistening and softening operation consists generally in inserting the toe portion of the upper and adjacent fore part of the inner sole of the shoe into the chamber of a steam box where the parts will be subjected to the influence of steam introduced into the box or other hot aqueous vapor therein.

The process is accompanied with many difficulties prominent among which is the danger of injuring the upper or the sole depending upon which is subjected to the most direct influence of the steam. Conditions which result in a satisfactory softening of the upper tend also to soften the sole, thus making the sole unworkable. When live steam is employed the escape of the steam around the opening through which the toe is inserted is also an objectionable feature.

It is accordingly among the objects of my invention to overcome in a very simple way and even when live steam is employed, all of the difficulties above referred to. In other words, by my present device I am enabled to eliminate all danger of injuring the upper or the sole. I am enabled, also, to soften only the upper without affecting the sole and am also enabled to prevent the escape of the steam.

The invention can best be seen in the light of the drawings, in which—

Figure 1 is a front elevation. Fig. 2 is a section on the line 2—2 of Fig. 1. Fig. 3 is a section on the line 3—3 of Fig. 1.

Referring to the drawings:—1 represents a receptacle for containing the softening

agent. Inasmuch as steam is the agent I prefer to employ, the receptacle may be characterized as a steam-box, steam being supplied to the chamber of the receptacle or box through a pipe 2 arranged in the bottom thereof. The receptacle or box has in the side 3 thereof one or more openings 4 through which the toe portion of the shoe is inserted to lie within the chamber of the box. I prefer that the side 3 of the box be fitted with a plurality of these openings in order to accommodate a number of shoes, and I prefer, also, for purposes of convenience, that the side 3 of the box be removable in order that the shoes may be inserted within the openings and then the side applied to complete the box, the removable side being then secured in any suitable manner.

For purposes of illustration I have shown a shoe with the toe inserted within the chamber of the box, 5 indicating the upper of the toe portion or that to be softened, and 6 the sole portion of the toe which, as later will be explained, is not acted upon by the softening agent.

7 is a guard provided with a flanged edge 8 by which it is secured to the side 3 of the box. The retention of the guard is such that the guard proper will extend from the lower edge of the opening through which the shoe is inserted and bear snugly against the entire inserted portion of the sole, or that which would otherwise be subjected to the influence of the steam or softening agent. The guard is made of some substance impervious to the passage of steam through it and is preferably made of metal. The guard 9 is also preferably made of some resilient substance or metal in order that it may bear with tension against the inserted toe portion of the shoe and thereby by its pressure hold the shoe in place within the opening, the action of the guard then operating to press the shoe against the opposite wall of the opening. The shoe is also supported in practice outside the receptacle or box by a suitable support (not shown) on which the heel or instep of the shoe may rest. Any suitable device may be employed for this purpose.

Secured to the side 3 of the receptacle or box is a curtain 9 made preferably in the form of a pocket to envelop the entire in-

serted toe portion of the shoe and the guard and make closed connection with the edge or the edges of the opening and there be secured in any suitable manner. This curtain 5 is made of any suitable substance, preferably of a flexible fibrous nature, which will protect the upper of the inserted toe portion from the direct contact of the steam or heated softening agent, which might otherwise injure it, permitting, however, the passage 10 through it of the heated aqueous vapor sufficient to soften the upper without injuring it. In practice I have found a medium heavy canvas cloth to be well fitted for such purpose, the canvas being simply tacked to the side of the box around the opening in it. The curtain thus arranged not only acts to protect the upper from the direct contact of the steam, but also prevents 15 the escape of steam from the chamber of the box through the opening as might otherwise be the case, owing to the fact that unless special provision be made steam will escape through the opening around the shoe.

20 In the operation of the device the pocket-forming curtain which envelops the toe acts as above described to protect the toe from the direct contact of the steam, but permits of the passage through it of the aqueous vapor modified in such manner that it will operate to properly soften the upper without any danger of injuring it. Were it not for the guard the softening agent or vapor might operate to soften the sole of the inserted 25 portion of the shoe, which is very undesirable, and this is prevented by the close-fitting guard which prevents the steam or aqueous vapor contacting with the sole, the sole, in other words, being maintained 30 in its original dry state so that the shoe may be immediately worked upon during the ensuing lasting operation.

Having thus fully described my invention, I claim and desire to secure by Letters 45 Patent of the United States:—

1. In a device of the character specified, the combination comprising a receptacle having in it an opening through which the toe portion of a shoe may be inserted to lie 50 within the chamber of said receptacle, means whereby steam may be supplied to the chamber of said receptacle, a guard impervious to the passage of steam arranged to closely engage the sole of said inserted 55 toe portion of the shoe whereby the steam or hot aqueous vapor arising therefrom may not engage said sole and soften the same, and a curtain arranged to envelop the upper of said inserted sole portion of the shoe for 60 protecting the same from the direct contact of the steam but permitting the passage through it of heated aqueous vapor sufficient to soften said upper without injuring it.

2. In a device of the character specified, 65 the combination comprising a steam box having in it an opening through which the toe portion of a shoe may be inserted to lie within the chamber of said box, means whereby steam may be supplied to the 70 chamber of said box, a metallic guard arranged to closely engage the sole of said inserted toe portion of the shoe, and a cloth curtain arranged to envelop the upper of said inserted sole portion of the shoe. 75

3. In a device of the character specified, the combination comprising a receptacle adapted to receive the toe portion of a shoe within the chamber therein, means for supplying said chamber with a softening agent, 80 and a guard impervious to the passage of said softening agent covering the sole of said inserted toe portion of the shoe and in close contact therewith whereby the softening agent cannot contact with the sole and 85 soften it.

4. In a device of the character specified, the combination comprising a receptacle adapted to receive the toe portion of a shoe inside the chamber thereof, means for supplying steam to said receptacle, and a pocket forming a curtain arranged to envelop the upper of said inserted sole portion of the shoe for protecting it from the direct contact of the steam but permitting 95 the passage of heated aqueous vapor therethrough sufficient to soften said upper without injuring it. 90

5. In a device of the character specified, the combination comprising a receptacle 100 having in it an opening through which the toe portion of a shoe may be inserted to lie within the chamber of said receptacle, means whereby steam may be supplied to the chamber of said receptacle, and a curtain having the general form of a pocket 105 for receiving within it said inserted portion of the shoe and making closed contact with said receptacle around the edge of the opening therein.

6. In a device of the character specified, the combination comprising a receptacle having in it an opening through which the toe portion of a shoe may be inserted to lie within the chamber of said receptacle, 115 means for supplying the chamber of said receptacle with a softening agent, and a resilient guard arranged to bear with tension against the sole of said inserted portion of the shoe protecting it from the 120 softening agent and holding the shoe with in said opening, substantially as described.

7. In a device of the character specified for softening the toe portion of a shoe, means for subjecting the upper of said toe portion to the influence of a softening agent, 125 and means impervious to said softening agent making close contact with the sole of

said toe portion of the shoe whereby said softening agent may not engage the sole and soften it.

8. In a device of the character specified for softening a portion of a shoe, means whereby the said portion of the shoe may be subjected to the influence of a steam bath,

and other means enveloping and protecting said portion of the shoe to be softened from the direct contact of the steam but permitting the passage through it of heated aqueous vapor to envelop said portion of the shoe to be treated and thereby soften it. 10

NAZZARENO SCARPONI.
